UNITED STATES PATENT OFFICE.

GEORGE H. WEBB, OF PAWTUCKET, RHODE ISLAND.

MACHINE FOR HEADING BOLTS.

SPECIFICATION forming part of Letters Patent No. 451,604, dated May 5, 1891.

Application filed March 27, 1890. Serial No. 345,575. (No model.)

To all whom it may concern:

Be it known that I, GEORGE H. WEBB, of the city of Pawtucket, in the county of Providence, in the State of Rhode Island, have invented a certain new and useful Improvement in Machines for Heading Bolts; and I declare the following to be a specification thereof, reference being had to the accompanying drawings.

10 Like letters indicate like parts.

Figures 1 and 2 are respectively a front and side elevation of the water box and drip, which constitute the main feature of my improvement. Fig. 3 is a front elevation of the cross-head of a bolt-heading machine with my improved water-box and drip in position. Fig. 4 is a vertical section on line XX of Fig. 3, the hammers and levers being in side elevation. Figs. 5 and 6 are detail views. Figs. 20 7, 8, and 9 show modified forms of my invention.

My invention relates to machines for heading bolts by "hot forging," and is designed to protect the hammer-slides from water and grit. The heading of the bolt is accomplished by an upsetting-die, which strikes the inserted end of the bolt-blank, and by forging dies or hammers, which shape the sides of the bolt-head. These latter hammers are mounted 25 on slides, which work in grooves or guides in the arms of the cross-head of the machine. The bolt-blank is highly heated, in order to be properly forged, and the dies or hammers which operate upon it would be injuriously heated were it not that jets of water are discharged upon them. As the heated bolt-blanks are struck repeatedly by the hammers scales of the iron fall off, as is common in forging, and these scales mingled with the water 30 will work their way, unless prevented, into the grooves or guides wherein the slides travel and will soon wear away both the slides and grooves by friction.

My invention consists in providing the usual 45 tubular guard, which surrounds the central or upsetting hammer, with a box-like extension in front, which has a convex water-drip at the bottom, extending laterally beyond the box portion, and also a convex trough secured 50 upon the upper end of the lower slide, which trough is so located as to take the discharge

of said drip and in turn to discharge upon the sloping surfaces cut in the cross-head or into a recess in the cross-head, as hereinafter more fully specified.

55

Referring to the drawings, A represents the cross-head of a bolt-heading machine. The arms are grooved to allow a reciprocating movement of the slides B therein. These slides B are operated by the levers C. On 60 each slide B is a hammering-die D, adjustably secured to the slide by the screw-bolt c. A screw-threaded rod a, engaging in a screw-threaded boss b of the slide B, is so adjusted that its inner end bears against the outer end 65 of the die D.

E is the upsetting die or hammer, which has a reciprocating movement in a direction at a right angle to the cross-head. The plunger of the die E is cut away on its under surface, as seen at d, so as to leave a water-drip at e.

70

Instead of the tubular guard usually surrounding the die E, I make a guard of peculiar construction. The rear portion m is tubular. The front extension n has three plane rectangular sides, which give it a box-like appearance, while the lower portion of this extension has a convex water-way or drip-box o projecting downward below the under surface 80 of the tubular part m and provided in front and rear with lips p p', the former extending downward to form a flange r. The lower inside surface of the tubular part m has a slight downward inclination toward the front to facilitate the flow of the water and the drip-box o is open at its lateral ends, as seen in Figs. 1 and 2. The cross-head A is cut away for the reception of this guard and drip-box and also to form convex surfaces s, terminating on each side with projecting dripping-points t, which discharge the water clear of the machine.

85

On the top of the lower slide B, which is shaped convex on its upper edge, I place a 95 trough G, longitudinally convex, (seen in front and side elevation in Figs. 5 and 6,) having lips u u' and ears v, by the latter of which it is fastened to the slide B. This trough G, I do not claim as my invention, the same being 100 shown in the pending application for Letters Patent filed by Benjamin S. Meader, Serial

No. 345,413. When the water has been discharged on the hammers D E to prevent their overheating, as already described, all the spray and spatters, as well as the scales of iron struck off by the operation of forging, collect in said central guard *m n*. The flow passes into the drip-box *o*, thence through the trough *G*, thence upon the sloping surfaces *s* of the cross-head, and falls to the ground from the drip-points *t*. By examining Fig. 4 it will be seen that the trough *G* is wider than the drip-box *o*, and therefore must conduct all its discharge away. The central guard has on the rear of its tubular portion *m* a concentric ring or circular lip *z*. The water falling from the plunger *E* drops from the point *e* inside the lip *z* of said central guard. The length of the tubular portion *m* of the central guard should be equal to the thickness of the cross-head *A*, as illustrated in Fig. 4, and the box portion *n* extends from the front of said cross-head into the open space left by the four slides *E*, as shown.

In Figs. 7, 8, and 9 I show at *G'* a guard-plate, which is a modification of the trough *G*. It has the same longitudinal curve, a front lip *w*, and ear-pieces; but its rear lip *y* is turned downward and the bottom in cross-section is slightly inclined sufficiently to conduct the water to the rear, where the lip *y* enters a recess *II* in the cross-head, whence the water flows from the machine to either side.

I claim as a novel and useful invention and desire to secure by Letters Patent—

- 35 1. In a bolt-heading machine, the combination, with a grooved cross-head and hammer-slides, of the central guard *m n*, having a drip-box *o*, arranged substantially as shown, and for the purpose specified.
- 40 2. In a bolt-heading machine, the combination, with a grooved cross-head and hammer-slides, of the central guard *m n*, having a drip-box *o*, and the convex trough *G* upon the top of the lower slide to receive and conduct away

the discharge of said drip-box to a recess in the cross-head, all located and arranged substantially as and for the purpose specified.

3. In a bolt-heading machine, the grooved cross-head cut away with sloping surfaces *s* on its lower arm, and an inner recess *II*, and the hammer-slides, in combination with the central guard *m n*, having the drip-box *o*, and the convex trough *G* upon the top of the lower slide, substantially as described.

4. The combination of the cross-head *A*, having a central aperture, the plunger and die *E*, reciprocating in said opening and provided with a dripping-edge *e*, and the central guard *m n*, having the concentric rear lip *z* and the drip-box *o*, substantially as specified.

5. The combination of the grooved cross-head having the recess *II*, the hammer-slides, the central guard *m n*, having the drip-box *o*, and the guard-plate *G'*, having the lip *w* bent up in front and the rear lip *y* bent down, said plate *G'* being fastened on the top edge of the lower slide *B* and adapted to discharge the drip of the box *o* into the recess *II*, substantially as shown.

6. The combination of the grooved and recessed cross-head *A*, the backwardly-inclined guard-plate *G'*, having the lips *w y*, and the slide *B*, to which said plate is fastened, substantially as specified.

7. In a bolt-heading machine, an upsetting die and plunger *E*, having an inclined cut *d* on its under surface to form a water-dripping edge *e*, in combination with the cross-head *A*, having a central opening, and a tubular guard inserted in said opening, and which is located and arranged so as to receive and conduct away the drippings from said edge *e*, substantially as shown.

GEORGE H. WEBB.
